 a British company

Application May 20, 1943, Serial No. 487,732
 In Great Britain July 17, 1942

9 Claims. (Cl. 178—44)

The present invention relates to gain control arrangements for carrier current transmission systems, and in particular concerns means for dealing with abnormal or faulty conditions in such systems.

In carrier current transmission systems it is now frequently the practice to provide automatic gain control arrangements for the purpose of adjusting the gain characteristics of the line repeaters in accordance with the changes in the attenuation of the line or other medium over which the currents are transmitted. This is usually done by transmitting one or more pilot currents with the signal currents over the communication path, which pilot currents will be subjected to the same changes in the medium as the signal currents, and are caused to vary the gain characteristics of the repeaters in the proper manner to compensate for these changes.

An increase in attenuation of the communication path will reduce the level of the pilot currents and this will be arranged to increase the gain of the repeaters. When the carrier system is operated over an open wire line, for example, the attenuation may vary between wide limits, and in exceptional circumstances (for example in conditions of sleet or snow) may become so much increased that it is impracticable to provide compensating means to deal with such an abnormal case, even if noise conditions do not render the circuit uncommercial. On the approach of the exceptional condition, or on the occurrence of a fault having an equivalent effect, the gain of the repeaters will increase to a maximum, and unless some action is taken, will remain at a maximum, which is undesirable for several reasons; and moreover it is necessary that an alarm should be given if the faulty condition persists.

Since in these carrier current systems it is usual for a proportion of the repeater stations to be unattended, it is very desirable that the means for dealing with the exceptional or faulty condition at these stations should be automatic, and moreover, that on the clearance of the fault, the unattended stations should return to normal without the necessity of a visit from an operator. In other words the repeaters should be self-aligning.

The present invention solves the above problem in a simple manner, and the solution provides as a by-product a valuable feature whereby a spare line can be provided with repeaters at unattended stations and can be brought into use without the necessity for the stations to be

visited to make the necessary adjustments. By means of the self-aligning feature, these adjustments take place automatically at each repeater station in turn as soon as the pilot currents are switched on at the terminal stations, or when a faulty section of line has been replaced.

The arrangements of the invention may also be applied in the receiving circuits of the group terminals in order to provide the self aligning feature and at the same time to prevent the occurrence of excessive noise on the circuit. It also prevents singing round the channels immediately after the last repeater has restored the transmission path while the gain of the group terminal receiving circuit is still high.

According to the invention, there is provided a multi-channel carrier current transmission system provided with one or more repeaters which comprise two oppositely directed one way amplifiers each of which is provided with an automatic gain control operated by one or more corresponding pilot currents, in which means is provided for introducing a large attenuation at the output of each amplifier when the level of any of the corresponding pilot currents departs by more than a predetermined amount from a given level.

According to another aspect, the invention comprises a multi-channel carrier current transmission system provided with one or more two-way repeaters, the transmission paths of which are blocked in both directions, comprising means for transmitting from each end of the system one or more pilot currents to the repeaters, means at each repeater controlled by the pilot currents for adjusting the gain thereof in such manner that for each direction separately the pilot current levels at the corresponding repeater output are brought to predetermined values, and means for unblocking the corresponding transmission path when the adjustment for the direction concerned has been completed, to allow the pilot currents to be transmitted to the next repeater.

The invention will be more clearly understood from the following detailed description with reference to the accompanying drawings in which:

Fig. 1 shows a block schematic diagram of a carrier current line repeater according to the invention;

Fig. 2 shows a schematic circuit diagram of a transmission cut-off circuit according to the invention; and

Figs. 3, 4 and 5 which should be placed side by

side, give a schematic circuit-diagram of the alarm and cut-off arrangements according to the invention.

Fig. 1 shows a block schematic diagram of a two-way repeater for a carrier current system showing the application of the invention. The system is of the kind in which different groups of carrier frequencies are used for transmission in opposite directions on the same line or communication path, the two directions of transmission being separated at the repeater by means of directional filters.

Signals arriving from line A are supposed to be conveyed on a high frequency group of carrier currents and are diverted by the directional filters to the lower half of the circuit and are applied to the regulating amplifier RAA, and then pass successively through a fixed equalising network NA, a line amplifier LA of fixed gain and a transmission cut-off circuit TCA, to the directional filter DFB and thence to the line B. Similarly, signals arriving from line B are conveyed on a low frequency group of carrier currents, and pass through a corresponding regulating amplifier RAB, equalising network NB, line amplifier LB, and transmission cut-off circuit TCB, to the directional filter DFA and thence to line A. Corresponding apparatus in the two halves of the circuit may differ in detail on account of the different frequency ranges concerned, but these differences are not significant as regards the present invention.

For the purpose of adjusting the gain of the repeaters, two separate pilot frequency currents are transmitted in each direction, the frequencies being suitably located in the corresponding transmitted ranges so as not to interfere with any of the channels. One of these controls the slope of the gain-frequency characteristic of the corresponding regulating amplifier in accordance with the changes in the form of the attenuation characteristic of the line, and the other controls the general level of the characteristic in accordance with the average increase or decrease of the attenuation. Thus for signals transmitted from the line A, the two pilot currents are transmitted through the regulating amplifier RAA and the equalizer NA and the line amplifier LA, and are there diverted to two pilot control panels SPA and GPA through separating filters in these panels, the output sides of which are separately applied to the regulating amplifier RAA. The panel SPA controls the slope and the panel GPA controls the level of the characteristic in a manner well known, which will therefore not be described. Similar pilot-control panels SPB and GPB are provided for the opposite direction and operate in the same way.

Each of the pilot control panels produces a rectified continuous voltage depending on the level of the corresponding pilot current at the output of the line amplifier LA or LB, this voltage being used to produce the necessary adjustment of the corresponding regulating amplifier. This voltage will be subject to small variations (depending on the degree of regulation obtained) while the line attenuation varies within wide limits, unless the gain control fails for any of the reasons previously explained.

According to the present invention, the rectified voltages from the two panels GPA and SPA are employed to control the same alarm panel ARA, in which an alarm relay is operated if the level of either pilot current departs by more than a specified amount from the standard level. In

the same way an alarm relay in a second alarm panel ARB for the other direction is controlled by the other pilot currents. The two alarm relays in turn control a common pulsing circuit PC which generates pulses for the purpose of repeatedly re-testing for the fault condition and cancelling the alarm if the fault does not persist. They also control independently of PC an alarm delay circuit ADC which, if the fault persists, ultimately operates the transmission cut-off circuit TCA or TCB which corresponds to the faulty direction, and gives the alarm. The transmission cut-off circuits are similar and operate to introduce a very high attenuation while at the same time accurately maintaining the impedance of the circuit at the proper value as seen from both directions. The circuit is thus practically cut although the repeater may be at maximum gain as a result of the fault.

These arrangements according to the invention which have just been briefly summarised will be explained in detail later on. It will be understood that only those details of the well known transmission arrangements necessary for understanding the invention have been shown in Fig. 1, and additional elements such as filters and equalisers may be provided as required. Also, there may be only one pilot current in either direction if slope adjustment, for example, is not required; or alternatively there may be three or more if other characteristics have to be controlled. In such cases there will be a panel such as SPA or GPA for each pilot, and each such panel will control the same alarm relay on either side, the operation of the circuit of the invention being the same for any number of pilots.

Fig. 2 shows the details of a preferred form of the transmission cut-off circuit TCA or TCB shown in Fig. 1. It comprises a bridge network of four equal resistances R, the input terminals 1, 2 being connected to one pair of diagonal corners, and the output terminals 3, 4 to the other pair. Terminals 1 and 2 are connected to the line amplifier LA, or LB in Fig. 1, and terminals 3 and 4 are connected to the directional filter DFB or DFA. A transmission cut-off relay T has two sets of change-over contacts t_1 and t_2 which in the un-operated position shown connect terminals 1 and 3 together and also terminals 2 and 4 together, short circuiting at the same time two of the resistances R occupying opposite arms of the bridge. The other two resistances are likewise disconnected at one end from the bridge corners connected to terminals 1 and 2 respectively. The terminals 1 and 2 are thus respectively joined straight through to terminals 3 and 4 without any intervening attenuation.

The winding of relay T is connected at terminals 5 and 6 to the alarm delay circuit ADC (Fig. 1) and when energised in a manner to be presently explained, the contacts t_1 and t_2 are caused to change over and to complete the bridge, the direct connection being now removed. As terminals 1, 2 and 3, 4 are now connected to the diagonals of a balanced bridge, transmission from one pair to the other will theoretically be impossible and the circuit is cut-off. At the same time the impedance seen from either pair of terminals will be R. In practice, of course, the bridge will not be exactly balanced on account of the manufacturing limits on the resistance values and also on account of stray capacities which cannot be eliminated altogether. In practice, however, the network can easily be made to introduce an attenuation of more than

60 decibels, which is sufficient for the purpose. The value of the resistance R should be chosen to be equal to the impedance of the circuit in either direction from the network.

Various arrangements other than that shown in Fig. 2 are of course possible for cutting the circuit or for introducing sufficient attenuation, while at the same time maintaining the cut portions properly terminated.

The details of the transmission cut-off and alarm arrangements are shown in Figs. 3, 4 and 5 which should be placed side by side with Fig. 3 of the left hand side. In these figures, an arrow pointing away from a relay indicates a grounded battery of suitable voltage.

Fig. 3 shows part of each of the two pilot control panels SPA and GPA for the A to B direction. In the panel SPA, two similar relays HS and LS have each two equal windings a and b of which the a windings are connected in series to the output of the rectifier circuit which produces the variable continuous voltage, indicated by the signs + and -, for operating the gain control. This is arranged to produce a certain current I_1 when the pilot level is normal. Connected to the terminals 5 and 6 there may be a voltmeter MS used for indicating the level of the pilot current.

The b windings of the relays HS and LS are connected in a local series circuit operated between a grounded positive battery connected to terminal 10 and ground at terminal 17 as shown. Adjustable resistances R_{28} and R_{29} are connected in series respectively with the relays LS and HS. The junction point (terminal 11) of R_{29} and LS is normally connected through conductor 9 and through a contact of relay FA in Fig. 4 to ground at terminal 10 in that figure, so that relay HS is normally short circuited.

According to a preferred arrangement, which, however, is only one possibility described to make the invention clear, the relays LS and HS are designed to operate on a net current of $3I_1/2$ and to release on a current of $I_1/2$. It will be noted that the currents I_1 and I_2 flowing in the windings a and b of relay LS are in opposition (the inner ends of both windings are designated "In"), so that the net current effective to operate the relay will be $I_2 - I_1$. The resistance R_{28} is adjusted so that for a normal pilot current level, $I_2 = 2I_1$, the net current being therefore I_1 , and the relay does not operate. In the case of the relay HS, since the current I_3 flowing through its winding b is normally zero as just explained, the net operating current will also be I_1 and it will not operate.

Should now the level of the pilot current fall until the current in the a windings of the relays is $I_4 = I_1/2$, then the net current in relay LS will be $I_2 - I_4 = 3I_1/2$, and the relay will operate; and the net current in HS being now $I_4 = I_1/2$, it still does not operate.

If the level of the pilot current should rise so that the current through the a windings of the relays becomes $I_5 = 3I_1/2$, then HS operates, but LS does not operate because the net current is now $I_2 - I_5 = I_1/2$.

It will thus be clear that with the adjustment described LS operates when the pilot level is low and HS operates when it is high. By suitable choice of I_1 , the pilot levels at which these relays operate may be fixed as desired. For example, these levels may be 3.5 db. above normal and 6 db. below normal.

The purpose of the winding b of relay HS and the associated resistance R_{29} is to allow a momentary release of these relays by the pulsing circuit PC (Fig. 5) in a manner to be more fully explained later on. When the pulsing circuit operates, relay FA (Fig. 4) removes the ground connection from terminal 11 of SPA (Fig. 3), and resistance R_{29} is adjusted so that the current I_3 which then flows through both relays is equal to I_1 . This will cause the momentary release of either relay when the pulsing circuit PC operates because the net operating current will in either case be reduced below the releasing limit $I_1/2$. If the fault is still on, the relays will operate again when the ground is replaced on terminal 11 by the pulsing circuit PC. The purpose of this arrangement is to allow robust telephone type relays to be used instead of expensive and delicate voltmeter relays which would otherwise be necessary owing to the small margin available between the operate and release currents. Furthermore, since the operation of the alarms depends on the values of the currents I_1 and I_2 , it is very desirable that the battery connected to terminal 10 (Fig. 3) which produces these currents should be a regulated battery.

The arrangements for the other pilot-control panel GPA are the same as those which have just been described for the panel SPA, the contacts of the corresponding relays HG and LG being simply connected in parallel with those of HS and LS so that they operate the alarm panel ARA (Fig. 4) in just the same way. A voltmeter MG may also be provided to indicate the pilot level, and when the alarm is given a reference to the meters MS and MG will show which of the pilot currents is at fault.

When either of the relays LS or LG of Fig. 3 operates, ground from terminal 10 of Fig. 4 is connected through conductors 7 and 6 to the relay LLA in the alarm panel ARA (Fig. 4), and this relay operates. Similarly if either of the relays HS or HG of Fig. 3 operates, relay HHA in the alarm panel ARA (Fig. 4) is operated from the ground at terminal 10 through conductors 7 and 8.

Both relays LLA and HHA (Fig. 4) have the same subsequent effect except in one particular to be presently mentioned. The sequence of operations is as follows:

On the operation of either of these relays, the alarm relay AL operates through an obvious circuit from ground at terminal 10. This relay prepares an operating circuit from terminal 19 for the pilot alarm signal relay PAS; it also prepares an operating circuit from terminal 14 for the relay FA; and it switches on the pulsing circuit PC and the alarm delay circuit ADC by short circuiting respectively terminals 15, 16 and 17, 18 (Fig. 4). This will be further explained presently.

When the alarm delay circuit ADC (Fig. 5) operates after a predetermined time, the pilot alarm signal relay PAS (Fig. 4) operates and lights a warning lamp PL and may also operate an audible alarm connected to terminal 5 if desired. This relay may clearly have other contacts (not shown) to perform other functions. At the same time the relay T in the transmission cut-off circuit TCA (Fig. 5) is operated through conductor 20, but only if relay LLA (Fig. 4) has operated; the resistance R_1 in series with the contacts of HHA being adjusted to prevent relay T from operating when HHA op-

erates first, but to allow T to be held by HHA once it has been operated by LLA.

The purpose of this arrangement is as follows:

The occurrence of a pilot current at an abnormally high level usually indicates a fault in the pilot equipment and not a line fault which would prevent the circuit from operating satisfactorily. Accordingly it would not be desirable to shut the system down for this reason. If the fault persists an alarm is, however, given when the alarm delay circuit ADC operates and the situation may be dealt with appropriately.

If the level of the pilot current is low, however, a line fault is usually indicated and it is necessary to shut down the system. Relay LLA operates in this condition and so the transmission cut-off circuit TCA operates, the alarm being given as before. After rectifying the fault, the pilot current will be restored and may be at an abnormally high level until the gain adjustment has taken place. It is not desirable to pass on the pilot current until the adjustment has been made, and accordingly HHA will operate and will hold the relay T operated through resistance R₁ although LLA will have been released. When the pilot current is back to its normal level, HHA finally releases, releases the relay T and switches off the pulsing circuit P. C. and the alarm delay circuit ADC (Fig. 5).

It will thus be appreciated that by the arrangement described, the circuit is cut off if the pilot level is low but not if it is high, but the cut-off is maintained when a low pilot level is immediately followed by a high pilot level.

If it should be desired to cut off the circuit also for a high pilot level, then the resistance R₁ may be omitted: and if this is done both the relays HHA and LLA perform the same function and one of them, for example HHA, may be omitted, terminals 12 and 13 of each of the panels SPA and GPA being connected together, and conductor 8 being omitted.

The pulsing circuit PC (Fig. 5) is a relaxation oscillator comprising a cold cathode gas filled discharge tube V₁ having a cathode y connected to ground at 3, a control electrode x and an anode z. When the relay AL in Fig. 4 operates to short-circuit terminals 15 and 16, the positive terminal 14 of a high tension supply, shown as a battery HT in Fig. 5, is connected to the anode z through a smoothing filter comprising retardation coil L and a shunt condenser C₁, and through a resistance R a relay D and conductors 16 and 15. A potential dividing circuit R₁, R₄ is connected between the anode z and the cathode y of the tube V₁ and the junction point Z is connected through a resistance R₂ to the control electrode x which is connected to ground through a condenser C₂. As soon as the relay AL (Fig. 4) operates, the condenser C₂ begins to charge up until its potential reaches the ionising potential for the electrodes x and y. The tube then fires and the anode current operates the relay D. This discharges the condenser C₂ through a low resistance R₃, and also operates the relay E which cuts the anode circuit of V₁ so that the discharge is extinguished. Relay E also operates relay FA in the alarm panel ARA (Fig. 4) (since relay AL is already operated), which releases any of the relays HS, LS, HG, or LG which may have operated. Relay E is preferably a slow release relay so that it does not release immediately on the release of D when the discharge is extinguished. Relay FA is likewise preferably a slow release relay and in addition to releasing the

relays in the panels SPA and GPA (Fig. 3) also provides when operated, holding circuits for the windings b of relays HHA and LLA. The b winding is so designed that although it will not operate the relay alone, it will hold the relay up when once it is operated.

Resistances R₅ and R₆ are associated with relay D for the purpose of reducing surges in the anode circuit of the tube V₁ which might cause erratic operation.

Resistance R₇ is shunted across relay E to act as a spark quencher for the contact of relay D, and to increase the release time of relay E.

After the release of relay D, the condenser charges up until the tube V₁ fires again, the process being repeated indefinitely. Thus each time the tube V₁ fires the relays in the panels SPA and GPA are momentarily released. When the fault condition is cleared, the relays HS etc. will not be re-operated and the corresponding relay HHA or LLA will be released, breaking down the alarm circuit, which then restores to normal.

It will be observed that the relay HHA or LLA is held operated during the pulsing because when FA is released it will be energized from the relays HS etc. through the a winding, and when FA is operated it will be held through the b windings from relay FA. By making these relays slow to release they will hold up during the change-over period, but will release as soon as the corresponding relay HS etc. releases.

The period of the pulsing circuit depends on the time constant of the circuit R₂, C₂. This may be made variable by making R₂ and/or C₂ adjustable, so that the period can be set to any desired value, for example 2 seconds.

Thus as soon as a fault or abnormal condition arises, one of the relays HS etc. operates and starts the pulsing circuit PC which continually re-tests for the fault condition, say every 2 seconds, until the fault is cleared.

The alarm delay circuit ADC is in principle exactly the same as the pulsing circuit PC and has corresponding components which will not be again described, except that the slow release relay E of the circuit PC is represented by a quick release relay M which, however, does not on operation switch off the high tension supply. The tube V₁ accordingly only ionises once, giving a single pulse after a time determined by the values chosen for R₂ and C₂ and remains permanently ionised until the fault condition is cleared. The operation of the relay M operates the alarm signal relay PAS through conductor 19 (Fig. 4) as already explained and also permits the operation of the cut-off relay T in the circuit TCA, the circuit having already been prepared by relay J. It will be observed that the alarm delay circuit ADC is switched on at the same time as, but independently of, the pulsing circuit PC by the short circuiting of the conductors 17 and 18 by relay AL (Fig. 4). The values of R₂ and C₂ in ADC will be chosen to give a relatively long time for the building up of the charge in C₂ to the ionising potential (say 4 or 5 seconds) so that the circuit is not cut off and the alarm is not given unless the fault condition persists. This is for the purpose of preventing a shut down caused by momentary fault conditions, such as line surges, which do not persist. During the time when the condenser C₂ in ADC is charging up, the pulsing circuit PC is continually re-testing for the fault, and ensures that the arrangement will clear down as soon as the abnormal condition has disappeared.

The arrangements have been described so far for the A to B direction of transmission. For the opposite direction, there will be provided a duplicate alarm panel ARB (not shown) multiplied to the conductors 14 to 19 at the right hand side of Fig. 5 as indicated. This will have connected to it two pilot control panels SPB and GPB (also not shown) similar to SPA and GPA of Fig. 3. The corresponding transmission cut-off circuit TCB is shown connected to the relay M at the right-hand side of the alarm delay circuit ADC. The operation of the apparatus corresponding to the B to A direction will be as already explained for the A to B direction. It will be noted that on the occurrence of a fault affecting a pilot current in one direction, only that direction is cut off; but should both directions be simultaneously affected, as may frequently occur in bad weather, both directions will be cut off, and it is immaterial whether the faults in the two directions occur at the same or at different times.

It will be usual to supply one alarm delay panel for each complete repeater (Fig. 1) in the repeater station. However, the pulsing circuit PC may be shared between any number of repeaters in the station, and Fig. 5 shows how for this purpose the conductors 14, 15 and 16 may be extended to the other repeaters. The conductors 15 and 16 are connected to all the AL relays for the purpose of switching on the PC circuit when required, and the conductor 14 is connected to each of the F relays through the corresponding AL relay contacts as shown in Fig. 4.

It will be understood that if there is only one pilot current in each direction, one of the pilot control panels SPA or GPA and one of the panels SPB or GPB can be omitted without affecting the operation of the other. Similarly if there are three or more pilot currents, corresponding pilot control panels will be provided for each of them and they will be exactly like SPA or GPA, the terminals 11, 12, 13 and 21 of all the panels being multiplied together.

When the automatic gain control fails, because of the abnormal increase of attenuation due to bad weather conditions for example, it is frequently the practice to provide means for switching over to manual gain control, or to set each repeater at some predetermined fixed gain. This may allow some of the carrier systems on a route to be maintained in service. When this is done, it is necessary to provide means for cutting out the alarm and cut-off arrangements which have been described. For this purpose, the ground connection to the circuit ARA Fig. 4, may be taken through a key or relay contact K, as shown, so that it may be disconnected when the circuit shown in Figs. 3, 4 and 5 is not to function. The contact K may be associated if desired with the arrangements (not shown) for switching over to manual control or fixed gain so that the alarm and cut-off arrangements will be automatically cut out. It will be seen that when the contact K is opened, the relays AL and T will be prevented from operating.

The arrangements described in connection with Figs. 3, 4 and 5 provide a means whereby a spare line provided with one or more repeaters at unattended stations may be taken into service when required, without the necessity for an operator to visit these stations. Assuming that all the repeaters have been originally lined up, and the automatic gain control arrangements properly adjusted, the spare line may be brought into operation simply by switching on the pilot currents, or by

patching it to a line where the pilot currents are already present at the proper levels. There will generally be a signalling trunk available by means of which the power supplies may first be switched on to the spare repeaters by well known arrangements. The apparatus of Figs. 3, 4 and 5 will give the usual indication of a low level pilot and the current will be cut in both directions. When the pilot currents are switched on from the nearest attended station, the first repeater will line itself up to produce the proper pilot levels at the output. When this has been done, the cut-off circuit will indicate normal conditions and the line circuit will be completed by the release of relay T to enable the pilots to be transmitted at the proper level to the next station. This then proceeds to line itself up in the same way, passing on the pilots to the next station and so on. When one direction has been lined up in this way, the opposite direction may be automatically lined up likewise, or both directions may be lined up simultaneously, after which all the cut-off circuits will be restored to normal.

It will thus be seen that during this process the pilot currents can never be transmitted to line at an abnormal level, and there will be no danger of interference with other systems on the same route during the lining up.

What is claimed is:

1. A multi-channel carrier current transmission system provided with at least one two-way repeater, including means for transmitting from each end of the system at least one pilot current to said repeater, means at said repeater controlled by said pilot current for adjusting the gain thereof in such manner that for each direction separately the pilot current levels at the corresponding repeater output are brought to predetermined values, means for blocking the transmission paths during said adjustment, and means for unblocking the corresponding transmission path when the adjustment for the direction concerned has been completed, so as to allow the pilot currents to be transmitted to the next repeater, said blocking means including an attenuating network comprising a substantially balanced Wheatstone bridge network, the input and output terminals of which comprise, respectively, the two pairs of diagonally opposite corners of the bridge and located in the output sides of said amplifiers, so that they can be blocked by the introduction therein of a large attenuation, and including a transmission cut-off relay having contacts connected so as to insert said bridge network in the circuit when said relay is operated, and to cut out said network when said relay is released, whereby said relay acts as said blocking and unblocking means.

2. A system according to claim 1, in which the four arms of the bridge comprise, respectively, four resistances, each substantially equal to the impedance of the circuit at the point where said network is introduced thereinto.

3. A system according to claim 1, in which at said repeater there is also provided for each one-way amplifier a pilot control panel corresponding to each pilot current which controls said one-way amplifier, each of said pilot control panels including a high pilot relay which is so connected as to close a pair of contacts only when the corresponding pilot level is high, and a low pilot relay connected so as to close another pair of contacts only when the corresponding pilot level is low.

4. A system according to claim 1, in which a plurality of repeaters are provided, and at each

of said repeaters there is also provided for each one-way amplifier a pilot control panel corresponding to each pilot current which controls said one-way amplifier, each of said pilot control panels including a high pilot relay which is so connected as to close a pair of contacts only when the corresponding pilot level is high and a low pilot relay connected so as to close another pair of contacts only when the corresponding pilot level is low, said system including more than one amplifier and pilot control panel at each repeater and means for connecting in multiple, at all said pilot control panels, the contacts corresponding to all said high pilot relays, and also the contacts corresponding to all said low pilot relays, whereby a single circuit is responsive to all the high pilot relays and a single circuit is responsive to all the low pilot relays.

5. A multi-channel carrier current transmission system provided with a plurality of two-way repeaters, including means for transmitting from each end of the system at least one pilot current to said repeaters, means at each repeater, controlled by said pilot current, for adjusting the gain of said repeater in such manner that for each direction separately the pilot current levels at the corresponding repeater output are brought to predetermined values, means for blocking the transmission paths during said adjustment, and means for unblocking the corresponding transmission path when the adjustment for the direction concerned has been completed so as to allow the pilot currents to be transmitted to the next repeater, said blocking means including an attenuating network comprising a substantially balanced Wheatstone bridge network, the input and output terminals of which comprise, respectively, the two pairs of diagonally opposite corners of the bridge and located in the output sides of said amplifiers, so that they can be blocked by the introduction therein of a large attenuation, and including a transmission cut-off relay having contacts connected so as to insert said bridge network in the circuit when said relay is operated and to cut out said network when said relay is released, whereby said relay acts as said blocking and unblocking means, including at each of said repeaters, for each one-way amplifier, a pilot control panel corresponding to each pilot current which controls said one-way amplifier, each of said pilot control panels including a high pilot relay which is so connected as to close a pair of contacts only when the corresponding pilot level is high, and a low pilot relay connected so as to close another pair of contacts only when the pilot level is low, and also including at each repeater an alarm panel for each of said one-way amplifiers, including a high level slow release relay connected so as to be operated by any of the high pilot relays and a low level slow release relay connected so as to be operated by any of the low pilot relays.

6. A system according to claim 5, in which said low level slow release relay is so connected as upon operation to prepare the circuit of said transmission cut-off relay for operation after a predetermined delay, and in which said high level slow release relay is so connected as upon operation to hold said transmission cut-off relay

70 operated after the release of said low level relay, said high level relay also being connected so as to prevent the operation of said transmission cut-off relay if said high level relay operates before said low level relay operates.

7. A system according to claim 5, in which said low level slow release relay is so connected as upon operation to prepare the circuit of said transmission cut-off relay for operation after a predetermined delay, including as means for providing said delay a relaxation oscillation circuit comprising a gas discharge tube connected so as to produce a single pulse, and a time delay circuit determining the discharge of said tube, said time delay circuit including a condenser and a resistance and means for charging said condenser through said resistance, and another relay, said pulse being used to operate said other relay, which latter closes the circuit of said transmission cut-off relay already prepared by said low level relay.

8. A system according to claim 1, including a plurality of repeaters, in which at each of said repeaters there is also provided for each one-way amplifier a pilot control panel, corresponding to each pilot current which controls said one-way amplifier, each of said pilot control panels including a high pilot relay which is so connected as to close a pair of contacts only when the corresponding pilot level is high and a low pilot relay connected so as to close another pair of contacts only when the corresponding pilot level is low, said system also including a pulse generator connected so as periodically to release any high pilot relay or low pilot relay which has operated as a result of an abnormal pilot current level, and so as to allow the periodical reoperation of such relay or relays while said abnormal condition persists.

25 9. A system according to claim 1, including a plurality of repeaters, in which at each of said repeaters, there is also provided for each one-way amplifier a pilot control panel corresponding to each pilot current which controls said one-way amplifier, each of said pilot control panels including a high pilot relay which is so connected as to close a pair of contacts only when the corresponding pilot level is high and a low pilot relay connected so as to close another pair of contacts only when the corresponding pilot level is low, said system also including a pulse generator connected so as periodically to release any high pilot relay or low pilot relay which has operated as a result of an abnormal pilot current level, and so as to allow the periodical reoperation of such relay or relays while said abnormal condition persists, said pulse generator including a relaxation oscillator comprising a gas discharge tube connected so as to produce pulses at regular intervals, an interval determining circuit including a condenser and a resistance, and means for charging said condenser through said resistance, and another relay connected so as to be actuated by the pulses from said generator, and operative so as to release said high and low pilot relays.
